AUTOMATIC PRESS CONTROL SYSTEM

Walter Ernst, Mount Gilead, Ohio, assignor to
 The Hydraulic Development Corp. Inc., Wil-
 mington, Del., a corporation of Delaware

Application August 31, 1939, Serial No. 292,932

2 Claims. (Cl. 60—52)

This invention relates to presses, and in particular, to control systems for hydraulic presses.

One object of this invention is to provide an automatic press control system, wherein the press ram is halted at the end of its working stroke and held in its halted position for a predetermined period of time before being automatically reversed and retracted.

Another object is to provide an automatic press control system, wherein the press ram is halted at a predetermined point on its forward stroke by tripping a limit switch which sets in motion a time delay device adapted to alter the energization of the electrical press control circuit at the end of the period of time for which the device is adjusted, thereby reversing and retracting the press ram.

Another object is to provide an electrical press control system, wherein the press ram is halted and held under a predetermined pressure at a predetermined position on its forward stroke for a predetermined period of time as controlled by a time delay device, after which the pressure is automatically released and pressure fluid admitted to the push-back cylinders to retract the press ram.

The drawing shows one embodiment of a press having an automatic control system according to the invention, arranged in a diagrammatic circuit partly in section.

In general, the automatic press control system of this invention consists of a limit switch adapted to be shifted by the press ram at a position corresponding to the end of its working stroke, but reversal is delayed by the action of a time delay device. During the dwell thus provided at the end of the working stroke, pressure is maintained upon the workpiece at a predetermined amount. At the end of the time period for which the time delay device is adjusted, the latter opens its contacts and deenergizes the solenoid which actuates the press control system to place the press upon its forward stroke. The control mechanism then shifts the flow-control member or shift ring of the pump to its reversed delivery position, causing pressure fluid to be supplied to the push-back cylinders and withdrawn from the main cylinder, thereby retracting the press ram. When the press ram reaches the end of its return or retraction stroke, an arm attached to the ram actuates mechanism which places the pump flow-control member or shift ring in its neutral position and thus holds the press ram in its retracted location.

Thus the automatic press control system of 55

the invention, in brief, includes a pressure-responsive switch actuated by the control rod of the press at the limit of the working stroke, with a time delay device to provide a dwell and to prevent premature backing off of the press ram, a pressure-holding servomotor being provided with a reversible variable delivery pump to prevent a continuing rise of pressure during the time delay period. The particular arrangement shown in the drawing also utilizes a closed hydraulic circuit interconnecting the pump and press.

Referring to the drawing in detail, there is shown a press 10, a reversible variable delivery main pump 11 of the pressure-holding servomotor type, a make-up valve or shuttle valve 12 for supplying fluid to make up for any insufficiency, a fluid tank 13, a pilot pump 14, a control valve 15, a time delay device 16, a solenoid 17 for actuating the press control mechanism in one direction, a contactor 18 for controlling the energization of the solenoid 17, a press-reversing limit switch 19 for initiating the operation of the time delay device 16 and a push-button switch 20 for initiating the operation of the entire circuit.

The push-button switch 20 is provided as the simplest form of starting arrangement to furnish semi-automatic operation. It will be evident that the circuit may be enlarged to provide full automatic operation by circuits known to those skilled in the art.

The press 10 is shown diagrammatically for the sake of simplicity, and consists of a bed 21 connected by strain rods 22 to a head 23. Mounted on the head 23 is a main cylinder 24 containing a main plunger 25, to which is attached the press ram or platen 26. Also secured to the latter are push-back plungers 27 reciprocating in push-back cylinders 28 mounted upon the press bed 21. The press ram 26 is provided with an arm 29 for engaging a stop collar 30 upon the press control rod 31, the latter being reciprocably supported by the arm 32 mounted upon the press bed 21. The control rod 31 is urged upwardly by the compression spring 33, mounted between the collar 30 and the end of the arm 32.

The control rod 31 also carries an annular cam 34 near its lower end for closing the normally open reversing limit switch 19. The latter is provided with a switch arm 35 and contacts 36 and 37, maintained in a normally open condition by the coil spring 38. The control rod 31 also carries a collar or head 39 at its upper end, beneath which is a coil spring 40 providing a

cushioning stop for the platen arm 29. Separable from the control rod 31 but in contacting engagement therewith is the valve-lifting rod 41 of the valve 15. The latter serves to lift the valve plunger 42 when the platen arm engages the coil spring 40 and lifts the control rod 31 and valve-lifting rod 41 into the position shown in the drawing. A coil spring 43 urges the valve plunger 42 downwardly toward its seat 44 between the inlet chamber 45 and exhaust chamber 46. The latter is connected by the exhaust conduit 47 to the tank 13, whereas the former is connected by the by-pass conduit 48 with the pilot pump 14.

The valve 15 also contains a pressure relief plunger 49, urged downwardly by a coil spring 50 to close the passageway 51 leading from the conduit 48 to the chamber 52. The latter is connected by the passageway 53 to the exhaust chamber. Thus when pressure in the conduit 48 exceeds a predetermined maximum, it raises the pressure relief valve plunger 49 and escapes through the chamber 52, the passageway 53, the exhaust chamber 46 and the exhaust conduit 47, back to the tank 13. The valve-lifting rod 41 is provided with spaced collars 54 engaged by the yoked end of a lever 55, pivotally mounted upon the shaft 56 and pivotally connected to the armature 57 of the solenoid 17. The armature 57 is urged upwardly by the compression spring 58.

The main cylinder 24 is supplied with pressure fluid from the main pump 11 by way of the conduit 59, having a branch 60 communicating with a chamber 61 surrounding the pump centering piston area 62 upon the pump flow-control rod 63. The latter is connected to the shift ring of the reversible variable delivery pump 11, the opposite side of which is connected to the rod 64, threaded as at 65, to receive a hand wheel 66 for adjusting the thrust of a coil spring 67 mounted within the cylindrical spring casing 68. The spring 67 urges the shift ring of the pump in one direction in opposition to the pressure of the pressure fluid against the centering piston area 62. When the pressure in the main cylinder 24 rises to a sufficient height to overcome the thrust of the spring 67, it pulls the shift ring of the pump 11 to its neutral or no-delivery position. The pump 11 is of the radial piston type, well known to those skilled in the art.

The pump flow-control rod 63 beyond the centering piston area 62 is provided with an enlarged piston head 69, reciprocable within a cylinder 10 supplied with pressure fluid on its left-hand side by the conduit 71 connected to the pilot pump pressure conduit 48. When pressure fluid of a sufficiently high pressure is admitted through the conduit 71 to the inner end of the cylinder 10, it shifts the piston head 69 and pump flow-control rod 63 to the right, placing the shift ring of the pump in its reverse position so that pressure fluid is thenceforth discharged through the conduit 72 leading to the push-back cylinders 28. At the same time, in its reversed condition the pump 11 withdraws fluid from the main cylinder 24, through the conduit 59, as hereinafter described in connection with the operation of the circuit. The tank 13 is connected by a conduit 73 with the middle chamber 74 of the make-up valve 12, the valve member 75 of which is shifted to and fro by pressure existing in the conduit 72 or the conduit 59 so as to permit fluid to be drawn from the tank 13 into either the end chamber 76 or the end chamber 77. The end chamber 76 is connected by the

conduit 78 to the conduit 59, whereas the opposite end chamber 77 is connected by the conduit 79 with the conduit 72.

In addition to the press reversing limit switch 19 and the solenoid 17, the electrical circuit contains the time delay device 16 and the contactor 18, all of which are energized from the power lines 80 and 81. The power lines 80 and 81 are connected to the lines 82 and 83 leading to the solenoid winding 84 when the contactor coil 85 is energized so as to pull its armature 86 to the left and with it the switch blades 87, 88 and 89 into engagement with their respective contacts. The coil spring 90 holds the armature 86 and switch blades 87, 88 and 89 in a normally open condition when the contactor coil 85 is deenergized.

The switch blade 89 provides a holding circuit for maintaining the energization of the contactor coil 85 by way of the power line 81, the lines 91, 92, 93 and 94, the contacts 95 and 96 of the time delay device 16, and the line 97 leading to the power line 80. This holding circuit is maintained after the circuit between the lines 98 and 92 is broken when the operator releases the normally open push-button switch 20 after starting the circuit in operation. The press-reversing limit switch 19 is connected to the time delay device 16 by the line 99, and to the power line 81 by the line 100. The time delay device 16 is provided with a motor 101 which opens the contacts 95 and 96 a predetermined period of time after the energization of the motor 101, in a manner well known to those skilled in the art.

In the operation of the press control system of this invention, to start the press in operation the operator momentarily depresses the push-button switch 20. This action energizes the coil 85 of the contactor 16, causing the armature 86 to move to the left so that the switch blades 87, 88 and 89 engage their respective contacts. The energization is maintained through the holding circuit established by the switch blade 89, in the manner previously described. The consequent energization of the winding 84 of the solenoid 17 pulls the armature 57 downward, and rocks the lever 55 so as to push the valve-lifting rod 41 upward.

Assuming that the main pump 11 and pilot pump 14 are running, the unseating of the valve plunger 42 by this operation causes the discharge of the pilot pump 14 to be by-passed through the line 48, the chambers 45 and 46 and the conduit 47, to the tank 13. Thus no pressure is permitted to stand in the left-hand end of the pump-reversing cylinder 10, and the spring 67 consequently urges the rod 64 and pump shift ring to the left, placing the pump 11 upon stroke in a forward delivery position. When this occurs the pump 11 delivers pressure fluid through the conduit 59 to the main cylinder 24, forcing the main plunger 25 and press ram or platen 26 downwardly. At the same time fluid is withdrawn from the pull-back cylinders 28 through the conduit 72. The ram 26 descends until it reaches its pressing position, whereupon it performs its work. When it nears the end of its working stroke its arm 29 engages the collar 30 and pushes the control rod 31 and cam 34 downwardly, engaging the switch lever 35 and closing the contacts 36 and 37 of the normally open press-reversing limit switch 19.

The closing of the circuit between the lines 97, 99 and 100 energizes the time delay motor 101 so that the timing cycle is started. Mean-

while, the pressure built up in the main cylinder by the resistance of the workpiece backs up in the conduits 59 and 60 and chamber 61, where it acts against the centering piston area 62 to overcome the thrust of the coil spring 67 and pull the pump flow-control rod 63 and shift ring to their neutral position. The pump 11 then holds the pressure upon the main plunger 25 at a pre-determined maximum, depending upon the thrust of the spring 67 as adjusted by the hand wheel 66.

When the timing motor 101 has run the course for which it has been set, it separates the contacts 95 and 96, breaking the circuit between the lines 97 and 98 and deenergizing the coil 85 of the contactor 18. The latter then opens, deenergizing the winding 84 of the solenoid 17. The coil spring 43, which has been compressed by the energization of the solenoid 17, now pushes the valve plunger 42 downward into engagement with its seat 44, closing off communication between the chambers 46 and 45 and ending the by-passing of the pilot pump 14 through the conduits 48 and 47. The pilot pump 14 then delivers pressure fluid through the line 71 into the left-hand end of the pump-reversing cylinder 70, causing the large piston head 69 to overcome the thrust of the coil spring 67 and shift the pump flow-control rod 63 and shift ring past their neutral positions into their reversed positions. The pump 11, thus reversed, discharges pressure fluid into the conduit 72 and push-back cylinders 28, forcing the push-back plungers 27, main ram 26 and main plunger 25 upward upon their retraction or return strokes. At the same time the pump 11 withdraws fluid from the main cylinder 24 by way of the conduit 59.

When the main ram or platen 26 nears the end of its return or retraction stroke the arm 29 engages the coil spring 40 and lifts the control rod 31 by means of its head 39. This forces the valve-lifting plunger 41 upward a short distance so that it lifts the valve plunger 42 slightly off its seat 44. This action permits the pressure in the conduit 71 to be relieved slightly by a slight by-passing through the conduits 48 and 47, thus permitting the pump flow-control rod 63 and shift ring to return to their neutral or no-delivery positions. When the platen 26 tends to descend, however, the platen arm 29 releases the coil spring 40 and permits the control rod 31, valve-lifting plunger 41 and valve plunger 42 to descend, ending the by-passing action and permitting the pressure to be raised by the pilot pump 14 in the

conduit 71 and reversing cylinder 70. In this manner the shift ring of the pump 11 is maintained in its neutral or no-delivery position at the end of its retraction stroke, and the main ram 26 is held in its raised position and prevented from coasting downwardly.

It will be understood that I desire to comprehend within my invention such modifications as come within the scope of the claims and the invention.

Having thus fully described my invention, what I claim as new and desire to secure by Letters Patent is:

1. A hydraulic press control system comprising in combination, a liquid operable and reciprocable main plunger, a reversible pump for supplying pressure fluid to actuate said main plunger in opposite directions, a pilot pump feeding a hydraulic circuit for reversing said reversible pump, valve means controlling the supply of liquid from said pilot pump to said reversing circuit, means normally biasing said valve means into one position, a press control element comprising two axially aligned unconnected parts mounted for movement parallel to said main plunger, an electric operator having means connecting the same to the first of said parts whereby energization of said electric operator will operate said first part, said valve being connected to the first of said parts and adapted to be actuated thereby against said biasing means, means on said second part whereby the same may be actuated by said main plunger during part of its movement in one direction, both of said parts being actuated in the same direction by said main plunger and said electrical operator, additional means on said second part whereby movement of said main plunger in the opposite direction operates said second part in said opposite direction, an electric switch mounted for actuation by said second part, when the same is moved by said additional means, and means actuated by said switch for de-energizing said electric operator whereby said biasing means moves said valve means to reverse said reversible pump and cause the retraction of said main plunger.

2. The combination as claimed in claim 1 including a timing device adapted to be energized by the operation of said electric switch for delaying de-energization of said electric operator for a predetermined period of time.

WALTER ERNST.
